UNITED STATES PATENT OFFICE.

FERDINAND WETTERBERG, OF PERTH AMBOY, NEW JERSEY.

CAN-NOZZLE PLUG-SEAL.

1,124,083.

Specification of Letters Patent.

Patented Jan. 5, 1915.

Application filed June 4, 1913. Serial No. 771,631.

To all whom it may concern:

Be it known that I, FERDINAND WETTERBERG, a citizen of the United States, and a resident of Perth Amboy, in the county of Middlesex and State of New Jersey, have invented a new and Improved Can-Nozzle Plug-Seal, of which the following is a full, clear, and exact description.

My invention relates to plugs for can nozzles and has reference more particularly to plugs for varnish cans, having means which seal the plug in the nozzle of the can.

An object of the invention is to provide a simple, inexpensive and easily removable plug which has means for sealing the nozzle of a can.

The invention consists of the construction and combination of parts to be more fully described hereinafter and fully set forth in the claims.

Reference is to be had to the accompanying drawings forming a part of this specification, in which like characters indicate corresponding parts in all the views and in which:

Figure 1 is an elevation of a can embodying my invention; Fig. 2 is a section in elevation through same; Fig. 3 is a longitudinal section through the blank; and Fig. 4 is a plan view of same.

In using varnish great trouble is experienced with the nozzle of the can after the seal, as at present used, is removed from the nozzle. The air having access to the varnish after removal of the seal dries the same rapidly, particularly where the varnish is in a thin layer, as for example, in the nozzle after pouring out some of the varnish.

The drying of varnish in a nozzle greatly reduces the aperture in the same and therefore the nozzle must be cleaned, which is not an easy task to do without injuring the varnish in the can. To obviate this defect I have invented a seal for use in connection with varnish cans.

The can 5, as shown in the drawings, is provided with a nozzle 6, preferably of circular cross section and slightly diverging toward the mouth of the nozzle, so that the nozzle represents a frustum of a cone with the larger base forming the mouth of the nozzle. The nozzle 6 at the mouth is provided with a reinforced border 7. Fitting snugly into the nozzle is a plug 8 having a concentric cylindrical portion 9 normally

projecting above the reinforced portion 7 of the nozzle.

A blank 10 engages the cylindrical portion 9 by means of a central orifice 11. The blank 10 is in diameter larger than the reinforced portion 7 of the nozzle and is concentric with the same when fitted on the cylindrical portion 9 by means of the opening 11. The blank 10 is also provided with a tongue 12, so that when the border of the blank 10 is crimped about the reinforced portion 7 of the nozzle the blank forces the plug 8 into the nozzle 6, making a tight fit between the plug and the nozzle, while the tongue 12 is bent simultaneously against the exterior lateral surface of the nozzle 6. To prevent sticking between the plug 8 and the nozzle 6 a paper cup 13 is fitted on the plug; also, to make a perfect seal by means of the blank 10, the same is lined with a suitable layer 14 of paper or any other material.

When a can of varnish is sealed by means of a device as herein disclosed, the same is opened as follows: The tongue 12 is bent away from the exterior lateral surface of the nozzle and by means of it the blank 10 is pulled off from the reinforcing portion 7 of the nozzle, the plug 8 still remaining in the nozzle. The plug 8 can then be removed by simply pulling the cylindrical portion 9, and due to the provision of a paper layer, the same can easily be removed from the nozzle. The necessary amount of varnish can then be poured out of the can and the plug restored to its position. This will keep the air out of the can and also prevent the formation of a coat of varnish in the nozzle aperture.

Having thus described my invention, what I claim as new and desire to secure by Letters Patent is:

1. The combination with a can nozzle of a plug engaging the nozzle opening and a blank engaging said plug and nozzle and whereby said plug is locked in the nozzle, a part of said plug projecting from the nozzle through said blank.

2. The combination with a can nozzle of a plug engaging the nozzle opening and a blank having a tongue engaging said plug and nozzle and whereby said plug is locked in the nozzle, a part of said plug projecting from the nozzle through said blank.

3. The combination with a can nozzle having a reinforced border of a plug engaging

the nozzle and having a portion projecting above the nozzle; a blank having means engaging said portion of the plug projecting above the nozzle and the reinforced portion of the nozzle whereby the said plug is locked in the nozzle with said portion projecting through the nozzle; and a tongue rigidly associated with the blank and normally disposed adjacent the exterior lateral surface of the nozzle and whereby the blank can be removed from the nozzle and the plug.

4. The combination of a can nozzle diverging toward its mouth and having a reinforced border at the mouth; of a plug comprising a conical portion fitting snugly into the nozzle and a cylindrical portion concentric with the conical portion and projecting above the nozzle's mouth; a blank

having a central opening engaging the cylindrical portion of the plug and with its border engaging the reinforced border of the nozzle, said blank normally forcing said conical portion into the nozzle, thereby locking the same in the nozzle; and a tongue extending from the border of the blank normally disposed adjacent the exterior lateral surface of the nozzle and whereby the blank is removed from the nozzle and the plug.

In testimony whereof I have signed my name to this specification in the presence of two subscribing witnesses.

FERDINAND WETTERBERG.
